UNITED STATES PATENT OFFICE.

THEODORE C. FENTON, OF THE UNITED STATES NAVY.

SUPERPOSED TURRET.

SPECIFICATION forming part of Letters Patent No. 699,751, dated May 13, 1902.

Application filed May 24, 1901. Serial No. 61,762. (No model.)

To all whom it may concern.:

Be it known that I, THEODORE C. FENTON, lieutenant United States Navy, residing at Washington, in the District of Columbia, have 5 invented certain new and useful Improvements in Superposed Turrets; and I do hereby declare the following to be a full, clear, and exact description of the invention, such as will enable others skilled in the art to which it applies to make and use the same.

My invention relates to improved means for mounting guns on board ship; and it consists, essentially, of two independently-operative superimposed turrets, the lower turret carrying the heavier guns and the upper turret carrying lighter guns, whereby the guns in each turret may be trained independently, and yet the protection for the ammunition-hoist and mechanism for rotating both turrets may be secured without the necessity for duplication of parts that is experienced when the turrets are not superimposed.

My invention further consists in means for operating the two turrets together by a single motor or by motors adapted to rotate either one of the turrets.

My invention further consists in certain details of construction and combinations and arrangements of parts, that will be hereinafter 30 more fully described and claimed.

By mounting the two turrets one above the other the armor protection for the ammunition-supply and the gearing for turning the lower turret serve also as a protection for the 35 like devices used with the upper turret, and thus a considerable saving in weight, of great importance aboard ship, is secured, while at the same time the two turrets may be operated independently, if desired, and the heavy 40 guns may be trained upon one target and the lighter guns upon another target. I have also made provision for training the two turrets conjointly by the same motor or motors should the other motor or motors become 45 operative for any cause.

My invention will be understood by reference to the accompanying drawings, in which the same parts are indicated by the same letters throughout the several views.

50 Figure 1 represents a central vertical section through the two superimposed turrets

and the parts of the ship beneath the same. Fig. 2 is a sectional plan, the lower half of said figure showing a section along the line 2^a of Fig. 1 and the upper half of said figure showing a section along the line 2^b of Fig. 1, in both cases looking down. Fig. 3 represents a section through one-half of the turret along the line 3 3 of Fig. 2 and looking in the direction of the arrows, the guns being shown 60 in elevation. Figs. 4, 5, and 6 are detail views, the last two showing the mechanism for rotating the upper turret and for throwing said mechanism out of engagement when desired; and Fig. 7 represents a modification in 65 which the upper turret turns on roller-bearings supported by the lower turret.

A represents the spar-deck of the vessel, and B, C, D, and E represent lower decks or platforms, the last-named, E, being the inner 70 bottom of the ship. The structural details of the ship's hull not being a part of my invention will not be further described.

F represents a cylinder or casemate of armor, into which the cone H' of the lower turret H projects. The weight of this turret H rests on the cone-rollers I, mounted on the track f, supported by the frames F', and the lower turret is turned by means of the fixed rack F⁰ and the pinion U², as will be herein- 75 after described. The front of the turret H may be an inclined armor-plate H², as shown in Fig. 1, or this armor-plate may be cut away to provide the sighting-hoods shown at H in Fig. 7, or it may be vertical throughout, if 80 desired. The steps H³ lead into the turret H at the opening h³, and h⁴ represents a grating put over an opening in the top of the turret.

Above the lower turret H the upper turret K is mounted. The upper turret is provided 90 with sighting-hoods L. The front of the upper turret may be inclined, as shown at K², or the armor may be vertical throughout. Access may be had to the upper turret by means of the opening K³, closed by the door K⁶, (see 95 Fig. 2,) or by lifting the grating h⁴ and passing down through the aperture covered thereby. K³ represents a ladder for climbing up to the top of the upper turret. The upper turret is provided with a ring h', which is normally clear of the ring k', fast to the lower turret; but the two rings engage when the 100

upper guns are fired, thus affording a bearing in partial support against the tendency to shear off the upper end of the tube N.

Circular angle-irons k^2 and h^2 are secured to the upper and lower turrets, respectively, between which are vertical rollers M, which lessen friction in turning the upper turret in a seaway. Suitable peep-holes h are provided in either or both of the turrets. The upper turret is secured, as by means of the circular brackets k, to the tube N, which may be made of a single piece or of two or more concentric layers, two being shown in the drawings. In the device shown in Fig. 1 this tube is provided with a hydraulic piston N^2 at its lower end which projects into a cylinder P, closed by a stuffing-box p' and provided with a port p, fed with fluid-pressure through an opening p^0 , connected to any suitable hydraulic ram; but this hydraulic attachment may be omitted, if desired. The lower end of the tube N is coned outward, as at N', and rests on the rollers O, so that the entire weight of the upper turrets and the guns carried thereby normally rests on these rollers. The guns Z and Z' are preferably mounted in pairs in the two turrets.

The tube N is provided with double tracks R for the ammunition-cars R' and R², which are supplied with ammunition from the holder Q, which is mounted on the circular platform N³, fast to the tube N. Bearings C' may be provided for the tube N at one or more of the decks of the ship. The lower turret is supplied with ammunition by means of the tracks S and ammunition-wagons T.

The lower turret is turned by means of the pinion U², meshing in the rack F⁰, which pinion is carried on the shaft U and carries a worm-wheel U', driven by the worm w, connected to the armature-shaft of the electric motor W, which worm-gearing is thrown into a different operation by means of any suitable clutch W'. Instead of an electric motor and worm-gearing any suitable gearing may be adopted for rotating the lower turret. The upper turret is driven by means of the gearing shown in Figs. 1, 5, and 6, where X represents an electric motor swiveled at x to the deck C, having its armature-shaft x' provided with a worm X', engaging the worm-wheel Y. This worm is thrown in and out of engagement by means of the hand-lever X⁴ and link x², connected to the journal-bearing X², in which the outer end of the armature-shaft rotates. This hand-lever X⁴ is pivoted on the frame X³, fast to the body of the ship, and the hand-lever is held in the position for engaging the worm-gearing by means of the pin x³ and in the position for disengaging the worm-gearing by lifting out this pin x³ and moving the hand-lever outward and then putting the pin back in place. Any other suitable device for throwing the worm-gearing in and out of action may be adopted, if desired. Since it is necessary to allow the worm-gearing to yield when excessive strains are imposed, the well-

known form of friction engagement shown in Figs. 4 and 5 is provided for the worm-wheels for the lower and upper turrets, respectively. In Fig. 4 the worm-wheel U' is provided with a conical recess, in which the cone-disk u' is held in frictional engagement by means of the nut u. A somewhat-similar arrangement for allowing the worm-wheel of the upper turret to turn is shown in Fig. 5, in which the worm Y slips over the cone-ring Y', which is forced by means of the bolts n⁵, screwing into the flanges n⁸ and y'. The upper part of the work-wheel Y bears against a shoulder n⁴ of the set collar N⁴, fast on the tube N.

In the form of device shown in Fig. 7 instead of the bearing-rings h' and k' I provide the roller-bearing I, and the weight of the upper turret is taken upon the top of the lower.

It may happen that the engines for rotating either one of the turrets may be out of order and it may become desirable to turn the two back, in which case either one of the motors W or X is thrown out of action and the locking-bolt V is put into its socket, as shown in Fig. 7, and the two turrets may be turned by the engine or engines provided for turning one of the turrets only. Any suitable device for locking the two turrets together may be provided.

I do not claim as a part of my invention any specific motor or gearing for turning either or both of the turrets, provided that they may be rotated either separately or conjointly.

It will be obvious that various modifications in the herein-described apparatus may be made which could be used without departing from the spirit of my invention.

Having thus described my invention, what I claim, and desire to secure by Letters Patent of the United States, is—

1. The combination with a pair of turrets arranged one above the other, of independent means for rotating each turret separately, substantially as described.

2. The combination with a pair of turrets arranged one above the other, of independent means for rotating each turret separately, and means for locking said turrets together when desired, substantially as described.

3. The combination with a pair of turrets arranged one above the other, of independent means for rotating each turret separately, means for locking said turrets together when desired, and means for throwing the motive power of either turret out of action, substantially as described.

4. In a vessel, the combination with a supporting-platform, a lower turret revolubly mounted thereon, and means for rotating said turret, of an upper turret revolubly mounted above the lower turret, and independent means for rotating said upper turret independently of said lower turret, substantially as described.

5. In a vessel, the combination with a supporting-platform, a lower turret revolubly

mounted thereon, and means for rotating said turret, of an upper turret revolubly mounted above the lower turret, and independent means for rotating said upper turret independently of said lower turret, with means for locking the two turrets together when desired, substantially as described.

6. In a vessel, the combination with a supporting - platform, a lower turret revolubly mounted thereon, and means for rotating said turret, of an upper turret revolubly mounted above the lower turret, independent means for rotating said upper turret, with means for locking the two turrets together when desired, and means for throwing the mechanism for turning either turret out of action, substantially as described.

7. In a vessel, the combination with a supporting - platform, a lower turret revolubly mounted thereon, and a rack and pinion, with means for rotating said pinion, for rotating said turret, of an upper turret revolubly mounted above the lower turret, and independent means for rotating said upper turret, substantially as described.

8. In a vessel, the combination with a supporting - platform, a lower turret revolubly mounted thereon, and a rack and pinion, with means for rotating said pinion, for rotating said turret, of an upper turret revolubly mounted above the lower turret, and independent means for rotating said upper turret, with means for locking the two turrets together when desired, substantially as described.

9. In a vessel, the combination with a supporting - platform, a lower turret revolubly mounted thereon, and a rack and pinion with means for rotating said pinion, for rotating said turret, of an upper turret revolubly mounted above the lower turret, with means for locking the two turrets together when desired; and means for throwing the mechanism for turning either turret out of action, substantially as described.

10. In a vessel, the combination with a supporting - platform, a lower turret revolubly mounted thereon, and means for rotating said turret, of an upper turret mounted above the lower turret, a tube rigidly connected to said upper turret and projecting downward through said lower turret, and means for rotating said tube, substantially as described.

11. In a vessel, the combination with a supporting - platform, a lower turret revolubly mounted thereon, and means for rotating said turret, of an upper turret mounted above the lower turret, a tube rigidly connected to said upper turret and projecting downward through said lower turret, means for rotating said tube, and means for locking the two turrets together when desired, substantially as described.

12. In a vessel, the combination with a supporting - platform, a lower turret revolubly mounted thereon, and means for rotating said

turret, of an upper turret mounted above the lower turret, a tube rigidly connected to said upper turret and projecting downward through said lower turret, means for rotating said tube, means for locking the two turrets together when desired, and means for throwing the mechanism for turning either turret out of action, substantially as described.

13. In a vessel, the combination with a supporting - platform, a lower turret revolubly mounted thereon, and means for rotating said turret, of an upper turret mounted above the lower turret, a tube rigidly connected to said upper turret and projecting downward through said lower turret, apparatus for supplying ammunition to the upper turret mounted in said tube, and means for rotating said tube, substantially as described.

14. In a vessel, the combination with a supporting - platform, a lower turret revolubly mounted thereon, and means for rotating said turret, of an upper turret mounted above the lower turret, a tube rigidly connected to said upper turret and projecting downward through said lower turret, means for rotating said tube, apparatus for supplying ammunition to the upper turret mounted in said tube, and means for locking the two turrets together when desired, substantially as described.

15. In a vessel, the combination with a supporting - platform, a lower turret revolubly mounted thereon, and means for rotating said turret, of an upper turret mounted above the lower turret, a tube rigidly connected to said upper turret and projecting downward through said lower turret, apparatus for supplying ammunition to the upper turret mounted in said tube, means for rotating said tube, means for locking the two turrets together when desired, and means for throwing out of action the mechanism for turning either turret, substantially as described.

16. In a vessel, the combination with a supporting - platform, a lower turret revolubly mounted thereon, and means for rotating said turret, of an upper turret mounted above the lower turret, a tube rigidly connected to said upper turret and projecting downward through said lower turret, antifriction-bearings at the base of said tube for supporting the upper turret, and means for rotating said tube, substantially as described.

17. In a vessel, the combination with a supporting - platform, a lower turret revolubly mounted thereon, and means for rotating said turret, of an upper turret mounted above the lower turret, a tube rigidly connected to said upper turret and projecting downward through said lower turret, antifriction-bearings at the base of said tube for supporting the upper turret, means for rotating said tube, and means for locking the two turrets together when desired, substantially as described.

18. In a vessel, the combination with a supporting - platform, a lower turret revolubly mounted thereon, and means for rotating said

turret, of an upper turret mounted above the lower turret, a tube rigidly connected to said upper turret and projecting downward through said lower turret, roller-bearings at 5 the base of said tube for supporting the upper turret, means for rotating said tube, means for locking the two turrets together when desired, and means for throwing out of

action the mechanism for turning either turret, substantially as described.

In testimony whereof I affix my signature in presence of two witnesses.

THEODORE C. FENTON.
